CLAIM

The ornamental design for a fencing panel, as shown and described.

DESCRIPTION

FIG. 1 is a perspective view of the fencing panel of my new design.

FIG. 2 is a front view of the fencing panel of my new design.

FIG. 3 is a right side view of the fencing panel of my new design. The left side view is a mirror image of FIG. 3; and,

FIG. 4 is a top view of the fencing panel of my new design. The bottom view is a mirror image of FIG. 4.

The fencing panel has differently spaced horizontal wires or lines, in that the lower portion of the fencing panel has wires or lines spaced closer together than the upper portion.
